UNITED STATES PATENT OFFICE.

ALLEN R. CUSICK, OF ALLENDALE, ILLINOIS.

COMBINED LATCH AND LOCK.

SPECIFICATION forming part of Letters Patent No. 369,045, dated August 30, 1887.

Application filed December 24, 1886. Serial No. 222,433. (No model.)

To all whom it may concern:

Be it known that I, ALLEN RAMSAY CUSICK, of Allendale, in the county of Wabash and State of Illinois, have invented a new and useful Improvement in Combined Latch and Lock, which improvement is fully set forth in the following specification and accompanying drawings, in which—

Figure 1 is a view of my improved device 10 with the face-plate removed; Fig. 2, an external perspective view of a portion of the same, and Fig. 3 a perspective view of the thumb-bolt detached. Fig. 4 is a top view of the bolt, showing the double bevels.

15 My invention relates to an improvement in combined latches and locks, wherein the special improvement consists in dispensing with one of the bolts ordinarily used in locks, and in lieu thereof I provide a single bolt and 20 bevel the opposite faces of the front end, so as to avoid the necessity of reversing when used for right and left hand doors, the key for locking and unlocking, and the knob-spindle disposed so as to act directly upon this bolt, a 25 right-angled lever within the device connecting with a second lever, which has a knob end projecting forwardly from the case for operating, so disposed as to be locked and unlocked by means of an ordinary key, this 30 right-angled lever being, however, disposed with a dead-latch to be operated from the inside of the door, so that the bolt cannot be operated either by the key or knob-spindle, all of which will now be fully set forth.

35 In the accompanying drawings, A represents the case of an ordinary door-latch provided with a bolt, B, the extreme outer end provided with opposite bevel faces, so that it may be used on either right or left hand doors 40 without reversing. This bolt is provided with a spring, C, so disposed that, except when the bolt is retained in position by the internal attachments, its normal position will be with the end projecting from the case, as shown in Fig.

45 1. The forward end of the bolt B, just within the case, is provided with a lug, D, so disposed as to come in contact with the inner face of the case-flange, while the inner face, E, of the said lug is somewhat inclined. Above the 50 bolt B, I provide a lever, F, the upper arm, G, projecting through the upper wall of the case,

and provided with a suitable knob for operating, while a lower arm, H, is so disposed as to come in contact with the inner angled face, E, of the lug D, when the upper arm, G, of the lever is pulled forward, but which rests above the upper edge of the said lug D when the lever F is reversed.

Just within the upper wall of the case I provide a right-angled lever, I, pivoted near the 60 lever F, just within the case, with the angled arm J projecting downwardly and having a recess, K, therein, within which a lug, L, on the projecting arm of the lever F rests. The usual key-hole, M, is disposed through the 65 case within the angle formed by the two sides of this lever I. The lever F is provided directly opposite the center with two projecting lugs, N, so disposed that the wards of the key will engage therewith when it is turned in the 70 lock. Upon the bolt O, to which the lever I is pivoted, is also pivoted a bar, P, which extends down and engages directly with the upper face of the bolt B, and the lugs N of the lever F are disposed immediately over the upper 75 end of this bar P. At the end of the lever I is a small bolt, Q, pivoted to the latch-case and operating in engagement with said lever, which bolt has an outwardly-projecting thumb-piece, R, extending through the top of 80 the latch-case, while the inner end has a shoulder, S, so that when the outer end is turned by means of the thumb-piece R the lever I will be held in position parallel with the upper wall of the case A, and it will be necessary to 85 disengage the shoulder S from the lever I in order to reverse the levers I and F or the bolt B from the position shown. Lugs T are placed near the end of lever I and project partly through the opposite face of the case A. By 90 depressing these lugs the lever I may be reversed, unless the lever is firmly held by engagement with the shoulder S.

Having described my invention, what I claim as new is—

1. In a combined latch and lock, a bolt having an inwardly-projecting lug, in combination with a pivoted lever, F, adapted to be moved both by hand and key into operative engagement with said lug, a right-angled lever, I, pivoted upon the latch-case and engaging said lever F, and a bar, P, operating in conjunction 95
100

with levers F and I and engaging the upper face of the bolt to retract the same, substantially as and for the purpose set forth.

2. In a combined latch and lock, the combination, with a bolt having an inwardly-projecting lug, a pivoted lever, F, adapted to be moved both by hand and key into operative engagement with said lug, a right-angled lever, I, pivoted upon the latch-case and engaging said lever F, and having lugs T thereon projecting through the face of the latch-case,

of a bolt, Q, having a shoulder, S, for engagement with the end of the lever I, and a thumb-piece, R, projecting through the latch-case, substantially as and for the purpose set forth. 15

In testimony that I claim the foregoing I have hereunto set my hand this 4th day of August, 1886, in the presence of witnesses.

ALLEN R. CUSICK.
